HIS ATTORNEY

UNITED STATES PATENT OFFICE.

MORRIS W. POOL, OF NEW YORK, N. Y., ASSIGNOR TO THE MONARCH TYPEWRITER COMPANY,
OF SYRACUSE, NEW YORK, A CORPORATION OF NEW YORK.

TYPE-WRITING MACHINE.

No. 892,618.

Specification of Letters Patent.

Patented July 7, 1908.

Application filed March 10, 1905. Serial No. 249,416.

To all whom it may concern:

Be it known that I, MORRIS W. POOL, citizen of the United States, and resident of the borough of Brooklyn, city of New York, in 5 the county of Kings and State of New York, have invented certain new and useful Improvements in Type-Writing Machines, of which the following is a specification.

My invention relates more particularly to 10 the ribbon feed mechanism of visible writing machines or those machines wherein the writing is visible to the operator as it is written. In machines of this class employing a ribbon, the latter is usually controlled by a 15 ribbon carrier or vibrator, which term, as used herein, comprehends any device for moving the ribbon automatically to cover the printing point and for affording a movement of the ribbon to uncover the printing 20 point. In machines in which the ribbon vibrator has a single uniform throw, the type impressions will follow a straight line lengthwise of the ribbon. In my pending application, Serial No. 247,474 filed February 27, 25 1905, I have shown means to cause the type impressions to follow a plurality of predetermined paths lengthwise of the ribbon and parallel with each other, a construction which enables the inking surface to be more 30 uniformly and thoroughly exhausted than is possible in constructions wherein the ribbon vibrator has a single uniform throw.

One of the objects of my present invention is to improve the construction shown in my 35 said pending application, by increasing the number of the parallel paths of the type impressions on the ribbon, so that a uniform and complete exhaustion of the inking surface of a wider ribbon may be had.

Another object is to enable a ribbon having fields of different characteristics to be 40 employed.

Another object is to provide a construction wherein the type impressions on each 45 field of a ribbon of the last named kind will follow a plurality of paths parallel with each other and longitudinal of said field.

Another object is to enable the ribbon to be maintained quiescent and without the 50 printing field during printing operation.

Other objects will subsequently appear.

To the above ends the invention resides in the features of construction, arrangements of parts and combinations of devices to be

hereinafter fully explained and particularly 55 pointed out in the claims.

In the accompanying drawings, Figure 1 is a vertical front to rear sectional view taken about centrally, of one form of typewriting machine embodying my invention, parts of 60 the machine being omitted. Fig. 2 is a fragmentary front elevation of the upper part of the machine. Fig. 3 is a fragmentary rear sectional view taken on a vertical plane near the rear of the machine. Fig. 4 is a 65 fragmentary top plan view of part of the ribbon mechanism. Fig. 5 is a side elevation showing parts of the ribbon mechanism, some of said parts being in different positions from those in which they appear in 70 Fig. 1. Figs. 6, 7 and 8 are enlarged fragmentary top plan views, looked at from the rear, of parts of the ribbon mechanism. Fig. 9 is an enlarged fragmentary top plan view, looked at from the rear, of certain parts 75 of the ribbon mechanism in positions corresponding to the positions of the same parts indicated in Figs. 1, 3, 4, 6, 7, and 8. Fig. 10 is an enlarged fragmentary top plan view, looked at from the rear, of certain parts of 80 the ribbon mechanism in positions corresponding to those indicated in Fig. 5. Fig. 11 is an enlarged diagrammatic view showing the paths of the type impressions on the ribbon. Figs. 12, 13 and 14 are diagrammatic views illustrating the ribbon reversing mechanism.

The invention is shown as applied to a Monarch typewriting machine and it is therefore not considered necessary to refer 90 other than briefly to the general structure shown in the drawings.

Considering first Fig. 1 to 11 inclusive, the frame of the machine is composed of a base 1, posts 2 and top plate 3, the 95 posts being secured to the base and the top plate being fixed on the posts. Key levers 4 are fulcrumed on a fulcrum plate 5 secured at the rear of the base, each key lever being provided with a restoring spring 100 6. Pivoted at 7 to each key lever is a sub lever 8, the lower portion of which co-acts 105 with a fixed abutment 9 and the upper end of which is connected by a link 10 with a type bar 11 which is one of a segmentally arranged series. The type bars may be pivoted on a curved fulcrum wire 12 seated in a segmental type bar support 13, and may

be guided in radial slots 14; or the said type bars may be provided with other kinds of pivots and supports as preferred. The type bars are designed to coöperate with the front 5 face of a rotary platen 15 mounted in a carriage 16 which travels on balls 17 confined in grooves formed in the carriage bars or rails 18 and in oppositely grooved bars 19 fixed to stationary brackets 20. The carriage is provided 10 with a feed rack 21 which normally meshes with a pinion 22, the latter being operatively connected with an escapement wheel 23 the teeth whereof are adapted to coöperate in a known manner with escapement dogs 24 mounted in a pivoted dog rocker 25. The dog rocker or carrier 25 is provided with a horizontally disposed arm 26, the forward end of which is connected by a link 27 with an arm 28 projecting rearwardly from the middle of the universal bar 29, the latter having pivots 30 secured in the sides of the base 1. Secured 15 to the pivot rod 29 are side arms 31 which, together with the arm 28, serve to support a universal bar 32 extending from side to side of the machine beneath the series of key levers and the spacing levers (not shown) and designed to be swung downward about the pivots 30 whenever any of said levers are 20 depressed during the operation of the machine. A spring drum 33, pivoted at 34 in a fixed bearing 35, is connected by a strap 36 with the carriage 16 and tends constantly to draw said carriage leftward across 25 the top plate. Whenever the universal bar is depressed the feed dogs 24, coöoperating with the other escapement members in a known manner, permit the carriage to move one letter space to the left.

30 Ribbon spools 37 are pivotally mounted above the top plate of the machine one at each side thereof and forwardly of the platen. A ribbon 38 is wound upon said spools and passes from one to the other in front of the 35 platen. Each ribbon spool is secured at the upper end of a vertical shaft 39 which rotates in a fixed bearing 40, said shaft being provided at its lower end with a small beveled gear 41. Meshing with the beveled gear 41 is a beveled pinion 42 secured to the forward end of a horizontally disposed shaft 43 adapted to rotate in fixed bearings 44 and having fixedly secured to its rear end a beveled pinion 45. Adapted to coöperate with 40 the pinion 45 is a driving pinion 46 fixedly secured on a driving or power shaft 47 which extends from side to side of the machine beneath the top plate and is slidably mounted in fixed bearings 48. The driving shaft 47 is connected with and is caused to rotate by the spring drum 33 through beveled pinions 49 and 50, the first named pinion being caused to rotate with the spring drum when the latter draws the carriage leftward and 45 the pinion 50 being so connected with the driving or power shaft 47 that the latter is caused to rotate with said pinion but has endwise motion independently thereof. It will be understood that each ribbon spool is connected as above described with a beveled pinion 45, there being one of the latter at each side of the machine as seen in Fig. 4. The beveled driving pinions 46 are so arranged upon the power shaft 47 that only one of said driving pinions is engaged at a 50 time with its associate pinion 45. To accomplish the alternate engagement of driving pinions 46 with their respective associate pinions 44 and thereby to cause the ribbon to wind from one spool to the other and vice versa, the power shaft 47 is moved endwise in any known manner. The preferred means of causing this endwise movement of the driving shaft is that shown in the U. S. patent to Jacob Felbel & Carl Gabrielson 55 No. 703,339, dated June 24, 1902, and hereinafter briefly described. With the parts arranged as shown in Fig. 4 of the drawings of this application, the ribbon may be caused to wind upon the left hand ribbon spool and to wind off the right hand spool. When all the ribbon has been wound off the right spool, the shaft 47 may, by the means explained in said patent, be shifted longitudinally in the direction of the arrow in Fig. 4 60 so as to cause the right hand driving pinion 46 to engage with its pinion 45 and the left hand driving pinion 46 to disengage from its associate pinion. The direction of the longitudinal feed of the ribbon is thereby reversed and the latter is caused to wind on the right hand spool and off the left hand spool. It is to be understood, however, that I do not desire to be limited to the means for reversing 65 the ribbon winding or longitudinal feeding mechanism explained in said patent. Any other automatic reversing means may be used with my invention, or the ribbon may be manually reversed as by pulling out or pushing in the handles 51, secured to the ends of the driving or power shaft 47 and ordinarily employed for rapidly winding the ribbon. A pivoted, vibratory, spring-pressed detent 52, engaging with a circumferential depression 53 in the driving shaft 47, serves 70 to retain the latter in either of its working positions and has the additional function of assisting to shift said shaft longitudinally from one working position to the other.

75 Centrally of the machine, the ribbon is threaded through a ribbon vibrator or carrier 54 which is guided and supported in grooves or tracks formed in the upright arms 55 of a supporting bracket 56 secured to the frame of the machine by screws 57. The lower end of the vibrator 54 is bifurcated and is provided with a cross pin 58 with which engages the slotted forward arm 59 of a two-part operating lever. The arm 59 terminates at the rear in a sleeve portion 60 (Fig. 120 80 85 90 95 100 105 110 115 120 125 130

6) which is perforated to receive a rock shaft 61 which serves as a fulcrum for the two-part lever. The rock shaft is provided at one end (the left end as viewed in Fig. 6) with an enlarged portion 62 which is formed with a cup-like depression 63, the purpose of which will be hereinafter explained. The rock shaft 61 is slidably and rotatively mounted in the bifurcated ear-like portions 64 of a bracket 65 depending from and fixed to the under side of the top plate. The collar portion 60 of the forward arm 59 of the two-part operating lever is located between the bearing ears 64 and the only motion of which said lever arm is capable, is a rotary one communicated by the rock shaft 61 when the latter is caused to rotate in a manner presently to be described. A set screw 66 is screwed into the collar portion 60, said screw entering a groove or depression 67 formed in the rock shaft 61 and extending lengthwise of the latter. The screw and slot connection just described enables a rotary movement to be transmitted from the rock shaft to the lever arm 59, while at the same time said rock shaft is capable of longitudinal movement independently of said lever arm. The perforated collar portion 68 of the rear arm 69 of the two-part lever is fixedly secured on the other end of the rock shaft 61 (the right hand end as viewed in Fig. 6) in any suitable manner, as by a rivet 70. The rear arm 69 of the two-part lever is formed with two slots 71 and 72. A link or actuating member 73 is pivoted at 74 to the right hand side (Fig. 3) of the arm 28 of the universal bar frame, and the upper end of said link is provided with a projecting stud 75 which is adapted to engage with the slot 71 in the lever arm 69 at the right hand side of the latter as viewed in Figs. 6, 7 and 8. A second link or actuating member 76 is pivoted at 74 to the arm 28 at the opposite side of the latter from the link 73, and said link 76 is provided at its upper end with a projecting stud 77 which is adapted to engage the slot 72 in the arm 69 from the left hand side of the latter as viewed in Figs. 3, 6, 7 and 8. A draw spring 78 has its ends secured to the links 73 and 76 and tends constantly, as best seen in Fig. 1, to draw said links together, being adapted to maintain the stud 75 at the forward end of the rear slot 71 and the stud 77 at the rear end of the forward slot 72. It will be noted that when thus positioned the forward edge of the link 73 is a short distance behind the driving shaft 47 while the rear edge of the link 76 is a short distance in front of said shaft.

As best appears in Figs. 3, 6, 7 and 8 the links 73 and 76 are oppositely off-set side-wise, so as to stand some distance apart transversely. The transverse relation of the two links is a fixed one, this result being accomplished by means of a right-angled guide

bracket 79. The upright arm of the guide bracket is secured to the bearing lug 65 by headed screws 80; and the rearwardly extending horizontal portion of the bracket 79 is formed with guide slots 81 and 82, the slot 81 receiving the link 73 and the slot 82 the link 76. The guide slots permit vertical and fore and aft play of said links but do not permit crosswise motion of said links confining them each to a single operating plane and thereby maintaining the studs 75 and 77 a fixed distance apart.

Fixedly mounted on the driving or power shaft 47 is a link controller or switch 83 which, as herein shown, is cylindro-conical in shape, comprising a circular face 84 concentric with the shaft 47 and a conical or tapered portion 85. The smaller end of the conical portion 85 terminates a short distance from the driving shaft 47. When the parts are arranged as shown in Figs. 4, 6, 7, 8 and 9, the small end or top of the cone-like portion 85 is, when viewed from the top and rear of the machine, slightly to the right of the link 73 and somewhat further to the right of the link 76.

Seated in the cup-like depression 63 in the rock shaft 61 is the inner end of a slide rod 86, the part of said slide within the cup-like depression being formed with a circumferential groove 87. A pin 88 is driven through the enlarged portion 62 of the rock shaft so as to engage the circumferential groove in the slide rod 86, as best appears in Figs. 3 and 6. This construction enables the rock shaft to be drawn endwise by the slide rod, while at the same time, said rock shaft may be rotated without affecting said slide rod. The slide rod 86 extends outwardly to the side of the machine passing through and bearing in one of the bearing lugs 44 and terminating exteriorly of the machine in a knurled finger button 89. Near its outer end the top of the slide rod is formed with a series of notches or depressions 90, 91 and 92. A locking spring 110 or check 93 is secured to the under side of the top plate by a headed screw 94, and said spring is adapted to engage the notches in the slide rod and thereby to retain the latter in any one of a plurality of predetermined positions.

The ribbon 38 shown in the drawings is one having a plurality of fields of different characteristics, being made up of two longitudinal stripes or fields *x* and *y*. Let it be assumed for purposes of illustration that these stripes *x* and *y* are colored respectively black and red; although it is to be understood that they may be colored in any other way or may instead differ in any other respect.

The operation of the parts will first be considered when they are positioned as indicated in Figs. 3, 4, 6 and 9, and it will be assumed for the time being that the positions indi-

cated in Fig. 1 correspond with those in the above named figures. When a key lever 4 is adequately depressed, motion is communicated through the universal bar arm 28 to 5 the links 73 and 76. With the parts positioned as now being considered the link 73 alone is in engagement with the operating lever, said link, it will be noted, having its stud 75 engaged with the front end of the 10 slot 71 in the rear arm 69 of the two-part operating lever. The movements of the link 76 will therefore be disregarded for the time being. As the link 73 moves downward it draws the arm 69 downward with it and the 15 latter being fixedly secured to the rock shaft 61, causes said rock shaft to rotate in its bearings 64 and thereby to swing the forward arm 59 upward about the rock shaft. As the forward arm 59 of the two-part lever 20 swings upward, it moves the ribbon vibrator 54 up until the ribbon covers the printing point. Wherein in the claims it is stated that the vibrator is moved or thrown to the printing point, I desire to be understood as 25 meaning that the vibrator is moved so as to cause the ribbon to cover the printing point on the platen. With the parts arranged as described the throw of the ribbon vibrator is a constant one and the mechanism is so pro- 30 portioned and adjusted that the type im- pressions will follow a path lengthwise of the ribbon somewhat above its center and repre- sented by the dotted line *a* (Fig. 11). The types will ordinarily contact with the ribbon 35 along the path *a* until the right hand ribbon spool is empty. When the ribbon has been completely unwound from the right hand spool the power shaft 47 is shifted longitudinally in the direction of the arrow in Fig. 4 in 40 a manner heretofore referred to, until the right hand beveled gears 46 and 45 are in mesh and the corresponding left hand gears are out of mesh. The longitudinal feed of the ribbon is thereby reversed and the said ribbon is 45 caused to wind on the right hand spool and off the left hand spool during the subsequent operation of the machine. As the shaft 47 moves longitudinally as just described, the link controller or switch 83 moves with it and 50 the cone portion 85 will contact with the front edge of the link 73 and will swing said link rearwardly about its pivot 74 against the pull of the draw spring 78.

The parts are so proportioned and ar- 55 ranged that when the switch has reached the limit of its movement in the direction of the arrows (Figs. 4 and 9) the link 73 will have been cammed or swung rearward until it engages with the circular face 84 of the switch 60 as indicated in Figs. 5 and 10. It will be noted that the rearward swing of the link 73 moves the stud 75 to the rear end of the slot 71 and further away from the rock shaft or fulcrum of the two-part operating lever, the 65 result being that when said lever is swung

upward during a printing operation it will carry the ribbon to a less height than when the stud 75 is at the forward end of the slot 71. As the printing keys are operated the switch 83 will rotate with the power shaft 47 70 and the circular face 84 will turn in contact with the forward edge of the actuating member or link 73. The stud 75 will thereby be maintained at the rear of the slot 71 and the forward arm of the operating lever will be 75 swung upward at printing operation so as to present a portion of the ribbon between the path *a* and the upper edge of the types. The latter will follow a straight line longitudinally 80 of the ribbon and parallel with and above the path *a*. The upper path is represented by the letter *b* (Fig. 11). The type impressions will follow the path *b* until the ribbon has been completely unwound from the left hand ribbon spool after which the power shaft 47 85 will be moved back longitudinally to the first described position with the left hand pinions 46 and 45 in engagement, and the longitudinal feed of the ribbon will be again reversed. The switch 83 returns with the power shaft 90 and as it does so, the draw spring 78 will swing the link 73 forwardly about its pivot 74 until said link reaches the position shown in Figs. 3, 4, 6, 9 and 1.

With the transverse relations of the actuating links and the operating lever un- 95 changed, the round of operations above de- scribed will be repeated indefinitely. The result is that the type impressions will follow a plurality of parallel paths longitudinal of the ribbon and confined to the field *x* thereof, so that all the type impressions will be black. From an inspection of Fig. 3 it will be seen 100 that for the "all black" position the notch 90 of the slide rod 86 is engaged with the spring 105 check 93.

Sometimes it is desirable, as in preparing stencils for mimeograph work, to cause the types to strike directly against the stencil or other paper without the interpositioning of the ribbon between them. Accordingly I have provided mechanism which prevents either of the links from actuating the operating lever, so that the latter will remain quies- 110 cent in normal position during the operation of the printing keys. To accomplish this result, the finger piece 89 is pulled outward until the notch 90 is disengaged from the locking spring or check 93 and the second notch 91 engages with said locking spring. 115 As the slide rod 86 is drawn outward it moves with it the rock shaft 61 which slides longitudinally in its bearings from the position indicated in Fig. 6 to that indicated in Fig. 7. The rear arm 69 of the two-part lever which is fixed to the end of the rock shaft is drawn 120 with the latter from the position indicated in Fig. 6 to that indicated in Fig. 7. It will be noted from an inspection of said figures that this movement of the lever arm 69 disen- 125 130

gages it from the stud 75 and causes it to take up a "neutral" position, between the studs 75 and 77 and disengaged from said studs. Since neither link is engaged with the operating lever, the ribbon, during the operation of the machine, will remain quiescent in normal position, and will not be interposed between the types and the paper.

If it be desired to print only on the red stripe y , the slide rod 86 is drawn still further outward or to the left as viewed in Fig. 3 until the second notch 91 disengages from the locking spring 93 and the third notch 92 engages with said spring. This further outward movement is transmitted to the rock shaft 61 and the lever arm 69 and the latter is moved from the position indicated in Fig. 7 to that indicated in Fig. 8 wherein it will be noted that the stud 77 of the link 76 is in engagement with the slot 72 in the lever arm 69. For purposes of illustration the positions of the parts indicated in Fig. 1 may for the time being be considered as corresponding to the positions indicated in Fig. 8. From an inspection of said figures it will be observed that the stud 77 is maintained at the rear of the forward slot 72 when the driving shaft 47 is positioned as indicated in Figs. 4, 8 and 9. The mechanism is so proportioned and adjusted that the type impressions will follow a path lengthwise of the ribbon and along the upper portion of the red stripe y , said path being indicated by the dotted line c (Fig. 11). When the ribbon has been completely unwound from the right hand spool, the power shaft 47, as heretofore explained, will be shifted longitudinally in the direction of the arrow (Figs. 4 and 9), thereby reversing the longitudinal feed of the ribbon. The switch 83 participating in the movement of the driving shaft 47 will change its relation with the link 76 from that indicated in Fig. 9 to that indicated in Fig. 10. It will be noted from an inspection of the last named figure, that the link 76 has been cammed forward slightly about its pivot 74 and that part of its rear edge is in contact with the cone portion 85 of the switch, the parts being maintained in this position during subsequent printing operations by the draw spring 78. For purposes of illustration, Fig. 5 may now be considered as corresponding with this last described relation of the parts. It will be noted from an inspection of said figure that the stud 77 has been moved to the forward end of the slot 72 nearer to the rock shaft or fulcrum 61. At printing operation the forward arm 59 of the two-part lever will throw the vibrator upward so as to present the lower portion of the red stripe y of the ribbon at the printing point. The throw of the vibrator being constant, the path of the type impressions will be in a straight line longitudinal of the ribbon and parallel with the path c as well as with

paths a and b . The lowermost path is indicated by the reference d (Fig. 11). The type impressions will follow the path d until the ribbon has been completely unwound from the left hand ribbon spool, after which, as hitherto explained, the driving shaft 47 will be moved back longitudinally to the first described position with the left hand pinions 46 and 45 in engagement, and the longitudinal feed of the ribbon will be again reversed. The switch 83 returns with the driving shaft, and as it does so the draw spring 78 will swing the link 76 rearwardly about its pivot 74 until said link reaches the position shown in Figs. 1, 8 and 9.

As long as the slide rod 86 is maintained with its notch 92 in engagement with the locking spring 93 the transverse relations of the lever arm 69 and the links 73 and 76 will be maintained as indicated in Fig. 8. Consequently the round of operations just described will be repeated indefinitely and the type impressions will follow a plurality of paths parallel with each other and confined to the red stripe y of the ribbon. If it be desired to return to the neutral or inactive position the slide rod 86 is pushed in until its second notch 91 is engaged with the locking spring 93. This return movement of the slide rod causes the lever arm 69 to be returned to the position indicated in Fig. 7, wherein neither of the actuating members or links is connected with said lever arm. If it be desired to return to the "all black" position (Fig. 6) the slide rod 86 is pushed inward until its notch 90 engages with the locking spring 93, which movement of the slide rod causes the lever arm 69 to reengage with the link 73 as indicated in Fig. 6.

While I have described the various operations of the mechanism in natural sequence it is to be understood that the devices may be manipulated in any desired order.

In order not to complicate the description of the invention proper, I have not hitherto described the means for automatically reversing the longitudinal feed of the ribbon. The preferred means, as heretofore stated, is explained in detail in the patent to Felbel & Gabrielson, No. 703,339, and it is thought sufficient at this time to describe the reversing mechanism briefly, reference being had to the said patent for a fuller description. Referring now to Figs. 12, 13 and 14 of the drawings of the present application, 95 designates an elbow lever pivoted to the under side of the right-hand ribbon spool 37, and for the greater part of the time retained in the position indicated in Fig. 13 by folds of the ribbon 38, which, it will be noted from an inspection of Fig. 12, is winding off the right-hand spool and on the left-hand spool. Until the right-hand spool is emptied the horizontal arm of the elbow lever 95 serves to retain in non-working position a cam plate 96

slidably secured to the under side of the ribbon spool. When the ribbon has been completely unwound from the spool it releases the upright arm of the elbow lever 95, therefore 5 by permitting the cam plate 96 to slide vertically downward to the position indicated in Fig. 14, in which position the outer cam face 97 is adapted to engage an upright pin 98 secured at one end of a horizontal spring mounted lever 99. The other end of the lever 99 normally contacts with and holds in rearmost position the upright arm 100 of a spring mounted slide rod 101, the rear end whereof is bent and terminates in a forwardly extending 10 trip pin 102. Normally the trip pin 102 is opposite to, but out of engagement with, a worm 103 fixedly secured to the driving shaft 47. After the cam plate 96 drops, the further turning of the ribbon spool ceases, the cam surface 97 acting upon the pin 98 to cam the horizontal lever 99 against the pressure of its spring 99^a to the position indicated in Fig. 12, thereby allowing the slide rod 101 to be moved forward by its spring 101^a until the trip 15 pin 102 engages with the worm 103. After this engagement takes place, the driving shaft 47, as it is rotated during the operation of the machine, will be wormed along in the direction of the arrow in Fig. 12, until the right-hand driving pinion 46 meshes with its associate pinion 45 and the corresponding left-hand pinions disengage, thereby reversing 20 the longitudinal feed of the ribbon. As the ribbon begins to wind back on the right-hand spool it will press the upright arm of the elbow lever 95 against the spool core, restoring said lever, and with it the cam plate 96, to the position indicated in Fig. 13. When the cam plate 96 is moved upward it releases the horizontal lever 99, permitting the latter to again act upon the slide rod 101 to push said slide rod rearwardly and restore the trip pin 102 to non-working position, it being understood that the spring 99^a is stronger than the spring 101^a. The left-hand ribbon spool is provided with a similar train of mechanism 25 which will operate in a similar manner when the said spool is emptied of the ribbon.

It will be noted that by my invention I have provided means for throwing the ribbon vibrator any one of a plurality of predetermined distances so that a type will strike at any one of a plurality of predetermined points in the width of the ribbon. Consequently the type impressions will follow a path first along one portion of the ribbon throughout its length or until the longitudinal feed of the ribbon is reversed and then the course of the type impressions will 30 be automatically changed to a path which will be parallel with and to one side of the first path so that the return track will not correspond with the first track. Furthermore I have provided means, when a ribbon

having a plurality of fields of different characteristics is in use, to confine the operations just detailed to any one of the fields of said ribbon that may be desired. The result is that the inked surface of each of the ribbon fields is uniformly and thoroughly exhausted 65 by my invention wherein are employed duplex widthwise ribbon-shifting means, one of said duplex means as herein shown being a switching member for positioning the links longitudinally of the operating lever and the other of said means being operated to cause 70 one or another of the links to actuate the operating lever.

While I have illustrated a two-color ribbon in connection with the invention it is to be understood that a one-color ribbon or a ribbon having uniform characteristics throughout may be substituted in a known manner for the two-color ribbon illustrated, and that the inked surface of said uniform ribbon may 85 be exhausted in the same manner as that of the two-color ribbon.

The Monarch machine, to which the invention is shown applied, shifts the type bar support in order to change case, so that the relation between the printing point on the platen and the ribbon vibrator is not altered when the case is changed and the path of the type impressions of the capital letters will be superimposed on the path of the impressions of the small letters. I do not desire, however, to be limited to this particular construction, as the invention may not only be employed with such a construction or with a construction which maintains in any other way a 90 fixed relation between the platen and the ribbon vibrator when the case is changed, but also with constructions wherein the relations between the printing point and the vibrator is altered when the case is changed. Furthermore, while the drawings illustrate one construction of mechanism for automatically moving the ribbon to cover the printing point when a printing key is depressed and for thereafter moving said ribbon to uncover the 100 printing point, it is to be understood that any other means of accomplishing this result 105 may be employed with the invention.

I prefer to employ a two-part operating lever, one part of which is shiftable relatively 110 to the other part transversely but not rotatively, said shiftable part or operating arm also altering its transverse relations with a plurality of actuating means, which latter are themselves maintained in a fixed transverse relation, but other means of accomplishing the results obtained may be employed.

Various other changes may be effected in the construction, arrangement and operation of the parts, and some of the parts may be used without others, all without departing from the spirit and scope of the invention.

What I claim as new and desire to secure by Letters Patent, is:—

1. In a visible writing machine, the combination of a ribbon; an automatic ribbon vibrator controlling said ribbon; means for feeding the ribbon longitudinally; means for reversing the longitudinal feed of the ribbon; and duplex means for shifting the ribbon widthwise, one of said duplex means being 10 operatively controlled by the ribbon reversing means.
2. In a visible writing machine, the combination of a ribbon normally removed from the printing point; means for feeding the ribbon longitudinally; means for reversing the longitudinal feed of the ribbon; and duplex means for shifting the ribbon widthwise; one of said duplex means being operatively controlled by the ribbon reversing means.
- 20 3. In a visible writing machine, the combination of a ribbon; a ribbon winding mechanism; means for reversing the ribbon winding mechanism; means for holding the ribbon normally away from the printing point; means for moving the ribbon automatically to cover the printing point; and duplex means for altering the extent of said automatic movement, one of said duplex means being operated by the ribbon reversing 30 means and the other of said duplex means being independently hand operated.
4. In a visible writing machine, the combination of a pair of ribbon spools; winding means therefor; means for reversing said 35 winding means; a ribbon carrier normally away from the printing point; means for moving said carrier to and from the printing point; and a plurality of means for altering the extent of movement of said carrier, one 40 of said last named means being operatively controlled by the ribbon reversing means.
5. In a visible writing machine, the combination of a pair of ribbon spools; winding means therefor; means for reversing said 45 winding means; a ribbon carrier normally away from the printing point; means for moving said carrier to and from the printing point; and duplex means for altering the extent of movement of said carrier, one of said 50 duplex means being operatively controlled by the ribbon reversing means and the other of said duplex means being operated independently of said ribbon reversing means.
6. In a typewriting machine, the combination of a pair of ribbon spools arranged one 55 at either side of the printing point; winding means for said spools; means for reversing said winding means; a ribbon carrier arranged between the spools and normally 60 away from the printing point; means for moving the carrier independently of the spools to and from the printing point; and a plurality of means for altering the extent of movement of the carrier, one of said last 65 named means being operated by the ribbon reversing means, and the other of said means being operated independently of said ribbon reversing means.
7. In a visible writing machine, the combination of a pair of ribbon spools arranged one 70 at either side of the printing point; winding means for said spools; means for reversing said winding means; a ribbon carrier arranged between the spools and normally 75 away from the printing point; means for throwing the carrier upward any one of a plurality of predetermined distances so as to cover the printing point during printing operation; and a plurality of means for altering the throw of said carrier from one to another 80 of said predetermined distances, one of said last named means being automatically operated and another of said last named means being independently hand operated.
8. In a visible writing machine, the combination of a carriage; a series of printing keys; a letter-spacing mechanism for said carriage; a universal bar operated by said printing keys; a ribbon; a ribbon winding mechanism; means for reversing said ribbon winding 85 mechanism; means actuated by said universal bar for moving the ribbon to and from the printing point; and a plurality of means connected with said ribbon winding mechanism for altering the to and fro movement of 90 the ribbon, one of said plurality of means being also connected with and operable by said reversing means and another of said plurality of means being independently hand operated.
9. In a typewriting machine, the combination of a ribbon vibrator; a lever for operating said vibrator; a pair of links, each operable upon said lever at one or another of a plurality of predetermined distances from its fulcrum; means for actuating said links; 100 means for automatically moving said links to cause them to engage with said lever at one or another of the predetermined points; and means for alternatively connecting said links with said operating lever.
10. In a typewriting machine, the combination of a ribbon carrier; an operating lever therefor; a pair of links each operable upon said lever at one or another of a plurality of predetermined points; means for actuating 105 said links; means for alternatively maintaining said links in engagement with the operating lever; and means for automatically moving said links to change the points of engagement with said lever.
11. In a typewriting machine, the combination of a ribbon carrier; an operating lever therefor; a pair of links each operable upon said lever at one or another of a plurality of predetermined points; means for actuating 110 said links; means for shifting said lever to cause it to engage alternatively with said links; and means for automatically moving said links to change the points of engagement with said lever.

12. In a typewriting machine, the combination of a ribbon carrier, a two-part operating lever therefor; a pair of links, each operable upon said lever at one or another of a plurality of predetermined points; means for actuating said links; means for moving one part of said lever relatively to the other so as to cause said lever to engage alternatively with said links; and means for automatically moving said links to change the points of engagement with said lever. 65
13. In a typewriting machine, the combination of a ribbon carrier; a two-part operating lever therefor; a pair of links each operable on said lever at one or another of a plurality of predetermined points; means for actuating said links; hand actuated means for moving one part of said lever so as to cause it to engage alternatively with said links; and means for automatically moving said links to change the points of engagement with said lever. 70
14. In a typewriting machine, the combination of a ribbon carrier; a rock shaft; a two-armed operating lever, said rock shaft being fixedly engaged with one arm and slidably engaged with the other arm of said lever; a pair of links, each operable on said lever at one or another of a plurality of predetermined points; means for actuating said links; means for moving said rock shaft endwise to cause said lever to engage alternatively with said links; and means for automatically moving said links to change the points of engagement with said lever. 75
15. In a typewriting machine, the combination of a ribbon carrier; a rock shaft; a two-armed operating lever, said rock shaft being fixedly engaged with one arm and slidably engaged with the other arm of said lever; a pair of links, each operable on said lever at one or another of a plurality of predetermined points; means for actuating said links; a hand actuated slide rod for moving said rock shaft endwise to cause the operating lever to engage alternatively with said links; and means for automatically moving said links to change their points of engagement with said lever. 80
16. In a typewriting machine, the combination of a ribbon vibrator; a single lever for operating said vibrator; a pair of links for actuating said lever; means for maintaining each of said links in a fixed relation with said lever; means for automatically altering said fixed relations and means for actuating said links. 85
17. In a typewriting machine, the combination of a ribbon vibrator; a single lever for operating said vibrator; a plurality of means each operative upon said lever at one or another of a plurality of predetermined distances from its fulcrum; and automatic means for moving said first named means to change their points of engagement with said lever. 90
18. In a typewriting machine, the combination of a ribbon carrier; a rock shaft; a two-armed operating lever, said rock shaft being fixedly engaged with one arm and slidably engaged with the other arm of said lever; a pair of links, each operable on said lever at one or another of a plurality of predetermined points; means for actuating said link; a hand actuated slide rod for moving said rock shaft endwise to cause the operating lever to engage alternatively with said links; a ribbon driving shaft; a link controller fixed to said shaft; and means for moving said shaft endwise to reverse the ribbon. 95
19. In a typewriting machine, the combination of a ribbon vibrator; a single lever for operating the same; a key actuated universal bar; a pair of links connected with said universal bar and operative upon said lever to throw said vibrator any one of a plurality of different predetermined distances; automatic means for altering the predetermined distance to which the vibrator is thrown; and other hand actuated means for also altering said predetermined distance. 100
20. In a typewriting machine, the combination of a ribbon vibrator; a slotted lever for operating the same; a pair of links, each provided with a pin adapted to engage a slot in said lever at different points; means for fixing the points of engagement between said links and said lever; means for automatically altering said points of engagement; and means for actuating said links. 105
21. In a typewriting machine, the combination of a ribbon vibrator; a slotted lever for operating said vibrator; a pair of links each provided with a pin adapted to engage a slot in said operating lever; means for automatically actuating either of said links longitudinally of said lever to one or another of a plurality of predetermined positions in engagement with said lever; means for actuating said lever transversely of said links for the purpose of alternatively engaging the latter; and means for actuating said links. 110
22. In a typewriting machine, the combination of a ribbon vibrator; a slotted lever for operating said vibrator; a pair of links each provided with a pin adapted to engage a slot in said lever; means for automatically actuating either of said links longitudinally of said lever to one or another of a plurality of predetermined positions in engagement with said lever; means for maintaining said links in a fixed transverse relation; means for moving said lever transversely of said links to effect alternative engagement with the latter; and means for actuating said links. 115
23. In a typewriting machine, the combination of a ribbon vibrator; a lever for operating said vibrator; a pair of links adapted to

actuate said lever; means for automatically moving said links longitudinally of said lever to predetermined positions; means for maintaining each of said links in a fixed plane of 5 operation; means for moving said lever transversely of said links to effect an alternative engagement with the latter; and means for actuating said links.

24. In a typewriting machine, the combination of a ribbon vibrator; a lever for operating said vibrator; a pair of links adapted to actuate said lever; means for automatically moving said links longitudinally of said lever to predetermined positions; means for maintaining each of said links in a single fixed plane of operation; hand actuated means operative exteriorly of the machine for moving said lever transversely of said links so as to engage with one or another of the latter at 20 will; and means for actuating said links.

25. In a typewriting machine, the combination of printing instrumentalities; a ribbon; means for feeding said ribbon longitudinally; a ribbon vibrator, means for throwing said vibrator any one of a plurality of predetermined distances so as to cause the types to follow any one of a number of predetermined, distinct paths longitudinal of said ribbon; and dual means for changing the 30 throw of said vibrator directly from one to another of said predetermined distances, one of said dual means being automatically operated and another independently hand operated.

35. 26. In a typewriting machine, the combination of printing instrumentalities; a ribbon, ribbon winding mechanism; a ribbon vibrator; an operating lever therefor; two actuating means adapted to act on said lever 40 at one or another of a plurality of predetermined points so as to cause the types to follow one or another of a plurality of straight, parallel and distinct paths longitudinal of said ribbon; means for automatically shifting 45 either of said actuating means from one to another predetermined points; and independent hand actuated means operative exteriorly of the machine for effecting engagement between said lever and either of said 50 actuating means.

27. In a typewriting machine, the combination of printing instrumentalities; a ribbon; means for feeding said ribbon longitudinally; a ribbon vibrator; an operating lever; a pair of actuating links; automatic means operative upon both said links to change their relation with said lever; and hand actuated means operative upon said lever to change its relation with said links, the 55 combination of said two means causing the printing types to follow any of a plurality of predetermined distinct paths longitudinal of the ribbon and parallel with each other.

60 28. In a typewriting machine, the combination of a ribbon vibrator; an operating lever

ver therefor; a plurality of actuating means each adapted to act on said lever at one or another of a definite number of predetermined separate points; means for automatically shifting said actuating means from 70 one to another of said predetermined points; and means for shifting said operating lever to engage alternatively with said actuating means.

29. In a typewriting machine, the combination of a ribbon vibrator; an operating lever therefor; a plurality of actuating means, each adapted to act on said lever at one or another of a definite number of predetermined points; a shifting member adapted to 75 shift said actuating means automatically from point to point; and independent hand actuated means for shifting said operating lever to engage alternatively with said actuating means.

30. In a typewriting machine, the combination of a ribbon vibrator; an operating lever therefor; a plurality of actuating means adapted to co-act with said lever in a plurality of predetermined fixed relations; and 80 dual means for changing from one to another of the predetermined fixed relations between the co-acting parts.

31. In a typewriting machine, the combination of a ribbon vibrator; an operating lever therefor; a plurality of actuating means adapted to co-act with said lever in a plurality of predetermined fixed relations; and dual means for changing from one to another of the predetermined fixed relations 90 between the co-acting parts, one of said dual means being automatically operated and the other of said means being independently hand operated.

32. In a typewriting machine, the combination of a ribbon vibrator; a lever for operating said vibrator; a pair of links, each operable upon said lever at one or another of a plurality of predetermined distances from its fulcrum; means for actuating said links; 100 means for automatically moving said links to cause them to engage with said lever at one or another of the predetermined points; means for alternatively connecting said links with said operating lever; and means 110 for rendering both said links inoperable on said lever.

33. In a typewriting machine, the combination of a ribbon carrier; an operating lever therefor; a pair of links, each operable on said lever at one or another of a plurality of predetermined points; means for actuating said links; means for alternatively maintaining said links in engagement with the operating lever; means for automatically moving 120 said links to change their points of engagement with said lever; and means for rendering both said links inoperable upon said lever.

34. In a typewriting machine, the combi- 125

nation of a ribbon carrier; an operating lever therefor; a pair of links, each operable on said lever at one or another of a plurality of predetermined points; means for actuating 5 said links; means for shifting said lever to cause it to engage alternatively with said links and for causing it to be disengaged simultaneously from both said links; and means for automatically moving said links 10 to change their points of engagement with said lever.

35. In a typewriting machine, the combination of a ribbon carrier; a two-part operating lever therefor; a pair of links, each operable upon said lever at one or another of a plurality of predetermined points; means for actuating said links; means for moving one part of said lever relatively to the other so as to cause said lever to engage alternatively 15 with said links or to disengage simultaneously from both said links; and means for automatically moving said links to change their points of engagement with said lever.

36. In a typewriting machine, the combination of a ribbon carrier; means for feeding the ribbon longitudinally; means for automatically reversing the longitudinal feed of the ribbon; and duplex means for shifting the ribbon widthwise, to write on different 25 portions of its width, one of said duplex means being automatic and operatively controlled by the ribbon reversing means.

37. In a visible writing machine, the combination of a ribbon; an automatic ribbon 35 vibrator controlling said ribbon; means for feeding the ribbon longitudinally; means for reversing the longitudinal feed of the ribbon; and duplex means for shifting the ribbon widthwise, each to a different predetermined 40 extent for presenting different fields of the ribbon to the action of the types, and one of said duplex means being operatively controlled by the ribbon reversing means.

38. In a typewriting machine, the combination of a platen; a vibratory ribbon carrier which normally maintains the ribbon removed from the printing point on the platen; an operating arm connected with said ribbon carrier; a plurality of means for actuating 45

said arm; and means for enabling each of 50 said plurality of means to be set and maintained in one or another of a plurality of predetermined relations with said operating arm, whereby said ribbon carrier may be thrown one or another of a plurality of extents by 55 each of said plurality of means.

39. In a typewriting machine, the combination of a platen; a vibratory ribbon carrier which normally maintains the ribbon removed from the printing point on the platen; 60 a pivotally mounted operating arm connected with the vibrator; a plurality of means for actuating said arm; and a plurality of means for changing the relations between said arm and said first recited plurality of means. 65

40. In a typewriting machine, the combination of types, a ribbon provided with a plurality of longitudinal stripes; a vibratory ribbon carrier which normally maintains the ribbon at an unvarying distance from the 70 printing point on the platen, means for throwing said carrier to and from the printing point; and means for altering the extent of the throw of the carrier to enable the types to coöperate with the ribbon at one or 75 another of a plurality of points widthwise of one or another of the plurality of stripes on the ribbon.

41. In a typewriting machine provided with a ribbon normally removed from the 80 printing point and having a plurality of fields of different characteristics, the combination of a platen; types; means for feeding the ribbon lengthwise; means for throwing the ribbon to cause the types to follow 85 parallel paths back and forth along one of said ribbon fields; and means for at will altering the ribbon field with which the types coöperate.

Signed at the borough of Manhattan, city 90 of New York, in the county of New York, and State of New York, this 9th day of March, A. D. 1905.

MORRIS W. POOL.
